UNITED STATES PATENT OFFICE.

FREDERICK J. CARNEY, OF ERIE, PENNSYLVANIA.

LUBRICATING-PUMP.

1,192,274.

Specification of Letters Patent. Patented July 25, 1916.

Application filed December 3, 1910, Serial No. 595,388. Renewed May 20, 1916. Serial No. 98,954.

To all whom it may concern:

Be it known that I, FREDERICK J. CARNEY, a citizen of the United States of America, residing at Erie, in the county of Erie and 5 State of Pennsylvania, have invented new and useful Improvements in Lubricating-Pumps, of which the following is a specification.

This invention relates to lubricating 10 pumps and it consists in the novel features hereinafter described and claimed.

The invention has for its object to provide 15 a device whereby the oil used for lubricating purposes in air compressors and the like may be used over and over again; the lubricant being conveyed from the compressor to a filtering device from whence it is conveyed by a pump to a lubricating receptacle which in turn feeds the lubricant by gravity 20 to the parts to be lubricated.

Another object of the invention is to provide a simple, improved and effective lubricating device.

Another object of the invention is to improve 25 the construction of the pump, whereby the lubricant is conveyed from the receiving compartment where the pump is located to the lubricating receptacle.

A further object of the invention is to 30 provide means for the return of the lubricant from the receptacle to the receiving compartment where the pump is located in the event of overfeed by the pump.

A further object of the invention is to 35 provide a simple and improved construction under which the pump shall be operated directly by the action of the compressor in connection with which the device is used.

A further object of the invention is to 40 provide simple and effective means for governing the stroke of the pump.

With these and other ends in view which will readily appear as the nature of the invention is better understood, the same consists 45 in the improved construction and novel arrangement and combination of parts which will be hereinafter fully described and particularly pointed out in the claims.

In the accompanying drawings has been 50 illustrated a simple and preferred form of the invention, it being, however, understood that no limitation is necessarily made to the precise structural details therein exhibited, but that changes, alterations and modifica-

tions within the scope of the claims may be 55 resorted to when desired.

In the drawings,—Figure 1 is an end elevation of an air compressor equipped with the improved lubricating device. Fig. 2 is a vertical sectional view enlarged taken 60 through the lubricating device, on the plane indicated by the line 2—2 in Fig. 1. Fig. 3 is a vertical sectional view taken through the pump on the plane indicated by the line 3—3 in Fig. 2.

Corresponding parts in the several figures are denoted by like characters of reference.

The oil box or casing A, which is equipped with a detachable lid A' contains a compartment B into which the used oil 70 from the compressor is conveyed through one of the openings 4 or 5, the other opening being meanwhile obstructed by a plug or stopper of suitable construction. The compartment B within the oil box A supports a filtering pan C which may be secured in position by suitable fastening means, such as bolts or screws 6. The pan C contains filtering material such as loosely packed wool which is held in place by means 80 of screens 7 of proper mesh. A screen 8 of angular or undulating form is placed midway in the filtering pan, said screen constituting a partition which permits a portion of the filtering material to be removed and renewed without disturbing the rest. A washer 9 of felt or other suitable material is placed beneath the filtering pan to prevent undue leakage of oil from the chamber B into the chamber D which is located adjacent to the chamber B, before 90 passing through the filtering pan C.

A pump E of special construction, which will be presently more fully described, is located within the chamber D for the purpose of raising the filtered oil from said chamber to the oil chamber or receptacle F. The latter is constructed preferably of a glass cylinder having top and bottom members G and H, the former of which is provided with an inlet plug 10. The bottom member H has a downwardly extending boss 11 which is connected by a pipe 12 with a chamber 13 formed in a projection 14 upon the casing A. The bottom member H 100 also has an upwardly extending boss 15 provided with apertures 16 opening into the lubricant receptacle. Threaded into the

boss 15 and extending downwardly through the pipe 12 is an internal pipe 17, the lower end of which communicates with the compartment D of the oil box A through a duct 5 or channel 18, the flow through which may be regulated by a valve plug 19. The upper end of the pipe 17 is connected by a coupling 20 with a tubular member 21 that extends through the top member G and has a head 22 bearing upon said top member which is thus assembled with the bottom member H and with the tubular glass 23 constituting the body of the lubricant receptacle. The tubular member 21 is provided 15 with apertures 24 opening into the lubricant receptacle directly beneath the top member G, thus permitting the contents of the receptacle when it rises to a certain stage to return to the compartment D of the oil box through the tubes 21, 17 and the port 18.

The external connecting tube 12 is connected by one or more pipes or ducts, as shown at 25, with various points to be lubricated on the compressor K to which oil will be fed by gravity or force feed, as may be desired.

The pump E, which is located in the compartment D of the oil box A, includes a cylinder 26 in which a piston 27 is arranged for reciprocation. The piston is moved upwardly and held in a raised position by the action of a spring 28. Said spring is coiled about a stop member 29 which limits and determines the extent of the downward movement of the piston. The latter is provided at either end with suitable washers 30 to insure a tight fit in the cylinder. The cylinder is provided at its upper end with a cap 31 having a port 32 and a union 33 serving to make fast the tubing or duct 34, whereby the pump cylinder is connected with a convenient point of the cylinder of the compressor. The lower cap 35 of the pump cylinder contains besides the stop 29 the upwardly and downwardly opening ports 36, 37 having valve seats, and equipped with ball valves 38, 39, the upward movements of which are limited by stop members 40 consisting of cross bars. The downwardly opening port 37 communicates with the interior of the compartment D of the oil box A, while the upwardly opening port 36 is connected by a duct 41 with the chamber 13 communicating with the lower end of the external oil pipe 12.

In the operation of this device, the used oil is conveyed from the compressor by the pipe 1, see Fig. 1, to the compartment B of the oil box. From this compartment it passes through the filtering device C to the compartment D from which the pump E forces it into the oil reservoir F.

The operation of the pump E is as follows: As the piston of the air cylinder of 60 the compressor moves toward the end of

said cylinder with which the tube 34 is connected, the piston 27 moves downward against the resistance of the spring 28, forcing the check valve 39 against its seat, and forcing oil from the pump up past the check valve 38 and through the duct 41 which leads through the chamber 13 and pipe 17 upward to the oil reservoir F. When the piston of the compressor cylinder reverses and travels on its return stroke, the air back 70 of the piston 27 expands, and the spring 28 then forces the piston 27 in an upward direction. The check valve 38 comes to its seat and obstructs the backward flow of oil to the pump from the reservoir F, while the check valve 39 is lifted from its seat, and another volume of oil enters the pump. Thus it will be seen that the downward movement of the piston 27 is caused by the compression within the compressor cylinder, 75 while the upward movement of the piston is caused by the expansion of the air back of the piston assisted by the pressure of the spring 28, and the resultant reciprocating motion of the piston serves to force the oil 80 to the reservoir F.

The volume of the oil, and the force of its delivery, may be controlled by the valve plug 19, and an auxiliary controlling valve 44 may be provided upon the duct 41.

It will be observed that by the use of this invention the lubricating oil after being used passes to the oil box where it is filtered and purified, after which it is forced by the pump to the oil receptacle or reservoir which constitutes a gravity feeding device. Said reservoir also constitutes a storage chamber which, in the event of accident to the pump, will maintain the supply of lubricant for a considerable period. The stroke of the pump 100 piston which governs the quantity of oil that is forced by the pump to the reservoir at each pulsation of the pump in order to maintain the supply in said reservoir is limited in an upward direction by the cap 31 and in 105 a downward direction by the stop member or buffer 29, which latter is to be of a predetermined length to properly regulate the stroke of the piston. In the event of over-feed, however, the surplus is returned to the oil box A through the internal pipe 17 and its connections. An air space is also maintained in the top of the oil reservoir which limits pulsations due to the pump and gives 110 an even pressure to the flow of oil.

While, in the foregoing, this invention has been described as being mainly applicable to air compressors, it is to be understood that the invention may be advantageously applied to other uses which will readily suggest themselves.

Having thus described the invention, what is claimed as new, is:—

1. A pump adapted to be automatically operated by the rise and fall of the pressure 115

within the compressor cylinder of an air compressor comprising a cylinder provided at one end with means for leading fluid pressures therein from the compressor, a cap closing the opposite end of the cylinder and adapted to rest upon a support and having a bore of the same diameter as that through the cylinder, said cap being provided at its side with a port which communicates with the interior of the cylinder, a piston slidably mounted in the cylinder and a spring interposed between the cap and the piston and being under tension with a tendency to hold the piston toward the pressure inlet end of the cylinder.

2. A pump adapted to be automatically operated by the rise and fall of the pressure within the compressor cylinder of an air compressor comprising a cylinder provided at one end with means for leading fluid pressure therein from the compressor, a cap clos-

ing the opposite end of the cylinder and having a bore of the same diameter as that through the cylinder, said cap being provided at its side with a port, a stop located 25 in the cap and having an end portion which extends above the lower side of the said port at the point through which it communicates with the interior of the cylinder, a piston slidably mounted in the cylinder and a 30 spring interposed between the cap and piston and surrounding the stop and being under tension with a tendency to hold the piston toward the pressure inlet end of the cylinder.

In testimony whereof I affix my signature in presence of two witnesses.

FREDERICK J. CARNEY.
